MAIL SORTING MACHINE

Isidore Becker, Bronx, N. Y.

Application January 16, 1946, Serial No. 641,456

7 Claims. (Cl. 211—10)

1

This invention relates to new and useful improvements in an automatic mail sorting machine.

More specifically, the present invention proposes the construction of a machine characterized by having an inclined continuous belt passing under a rack having passages for use in sorting mail headed for different destinations and having passages at right angles thereto for stacking mail for similar destinations, the last mentioned passages having containers therein for receiving stacks of mail and having spring devices for guiding the stacks as they form, the belt acting as a conveyor of individual letters along the first passages to the passages in which they are to be stacked.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an automatic mail sorting machine constructed in accordance with this invention.

Fig. 2 is an enlarged section on the line 2—2 of Fig. 1.

Fig. 3 is a fragmentary plan of the machine.

Fig. 4 is an enlarged detail of one portion of the machine.

Fig. 5 is an enlarged section on the line 5—5 of Fig. 3, parts being shown fragmentally.

Fig. 6 is a view similar to Fig. 5 with some letters stacked therein.

Fig. 7 is a perspective view of a box forming part of the machine.

Fig. 8 is a section on the line 8—8 of Fig. 7.

The automatic mail sorting machine, according to this invention, includes a table 10 supported on legs 11, and having shelves 12 at the front thereof, which may be used for sorting mail. A rear wall 13 upstands from the rear of the table. Inclined bearings 14 are provided at the ends of the front of the table, and inclined bearings 15 are provided at the top of the rear wall and supported by brackets 16 secured to the table.

An inclined shaft 17 is secured in the bearings 14 and 15 at each end of the table. An endless belt 18 extends over the two shafts 17, the belt being substantially as wide as the shafts 17 are long. The shaft 17 at the left side of the table is rotated by an electric motor 19 supported on a bracket 20 secured to the rear wall 13. The shaft 17 at the right end of the table is rotated

by a belt of the conveyor type, as will presently appear. The motor may be provided with a variable speed device (not shown) if desired.

A mitered rack 21 is provided above the endless belt, the mitering being at the right side thereof. This rack is inclined similar to the belt and is covered along its bottom by the belt which is in close proximity thereto. The rack has a front wall 22, a rear wall 23, a left side wall 24 and a right side wall 25. It is supported at its front on the table by means of brackets 26 and is secured at its rear to the top of the rear wall 13. The rear wall 13 may be a solid panel or may be merely an openwork support made of a plurality of bars.

10 The rack has no top wall but is reinforced across its top by several bridges 27 extending between and secured to the front and rear walls. The rack is rectangular and the walls are inclined at a substantially 45° angle.

15 The rack is divided interiorly into a plurality of longitudinal passages 28 by longitudinal vertical partitions 29, which are secured to the bridges 27. Each partition 29 is parallel to the walls 22 and 23. The rear partition extends from the left wall 24 to a point short of the right wall 25 the length of a long average envelope of letter size. At its right end it is joined (mitered) to a transverse vertical partition 30 which extends therefrom, parallel to wall 25, to the front wall 22.

20 Each of the other partitions 29 similarly extend to a partition 30, thereby providing transverse passages 31, each of the same width longitudinally of the machine but of different lengths transversely of the machine. The front passage 28 has no passage 31 meeting it and is therefore not used. The front passage 28 is the shortest passage 28, and the passages 28 get successively longer rearwardly, the rearmost being the longest. In the same manner, the passage 31 at the

25 right is the longest and the one at the left is the shortest. If desired these passages 31 may be so constructed as to be adjustable in their width in order to accommodate the different possible sizes of envelopes. Unlike the area covered by the greater part of rack 21, passages 31 are provided at their bottom with a flooring 31a secured to the underside of rack 21 and thus forming a platform on which envelopes may collect.

30 Each of the passages 31 may have therein a box 32, best shown in Figs. 7 and 8, which rests on flooring 31a. The box has a right wall 33 extending along the right side of its passage 31, a left wall 34 extending along the left side of its passage 31 to the intersecting partition 29, and a bottom wall 35. The bottom wall is rectangular in cross

section at any point along the length of the wall 34 but to the rear thereof it is tapered in cross section, as is clearly shown in Fig. 8. The sharp point of wall 35 lightly engages the top face of the endless belt.

A backing plate 36 is secured in each box 32. Each plate 36 has a rod 37 extending forwardly therefrom through an orifice 38 in the front wall 22. A very light compression spring 39 is mounted on each rod 37 between the front wall 22 and the backing plate. The springs are only sufficiently strong to normally hold the backing plates just within the rear edge of the wall 34 and may be compressed very easily by letters stacking in the box 32 as will presently appear.

The operation of the machine is as follows: Postal clerks, each sorting mail which he temporarily lays on the shelf 12 prior to sorting, drop letters in the passages 28. Ordinarily the passages 28 will be quite long and a number of clerks will be using the machine at one time. Each of the passages 28 is marked with a different destination, such as different States of the United States. There may be as many passages 28 as desired, and as many shelves 12 as desired, the number shown in the drawings being by way of example only. As the clerks drop letters in the passages 28, the conveyor belt supports the letters and moves them to the right toward the passages 31. The belt ordinarily moves slowly. The passages 28 are quite narrow so that the letters cannot fall over on their flat surface.

As the letters in the various passages 28 reach the passages 31, each is slid up on the flooring 31a or upon the tapered wall 35 of the box, depending upon whether or not the boxes 32 are being used. Should any letter stop before it is completely on the wall 35 the next letter coming along in the same passage 28 will push it completely upon the wall 35. The letters will each be stopped in its movement toward the right by the wall 33 and will be maintained in vertical position by the backing plate 36. Each letter that rests against the backing plate 36 tends to move it forwardly against the compression of the spring 39. This forward movement is further assisted by the fact that the passages 31 and therefore the boxes 32 incline downwardly and have an assisting gravitational force.

As the letters are moved along each passage 28 to each passage 31 and stacked in the boxes 32, the springs compress more and more until the boxes are full. As the boxes fill, the rods 37 slide forwardly through the orifices 38. When any one box is filled, it may be lifted out with the letters stacked therein. Before the box can be lifted out it must be moved rearward to clear the backing plate 36. The letters are indicated in the drawings by the letter A.

If boxes are not to be used at this stage it is merely necessary for the postal clerk to withdraw a stack of envelopes from any desired bin, and after recording the time, simply ties the bundle by means of an automatic tying machine and thus the mail is completely ready for the distribution rack.

The aforescribed device is adaptable to various construction and arrangements, such as one suitable for providing working and sorting space on both sides of the mail sorting machine, the construction being such that all functions would be performed by a single motor as previously described.

While I have illustrated and described the pre-

ferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

10. An automatic mail sorting machine comprising a table supported on legs and having a horizontal wall and a vertical wall, inclined shafts journaled in bearings supported on said walls at opposite ends of said table, means for rotating one of said shafts, a continuous belt extending around said shafts driving the other of said shafts from said one shaft, and a rack supported on said table in an inclined position on top of said belt, said belt underlying the entire bottom of said rack, said rack being partitioned into a plurality of longitudinal passages each terminating at one end at a juncture with a transverse passage, said transverse passages being inclined with said junctures at their tops whereby letters placed in said longitudinal passages will be conveyed therealong by said belt to said transverse passages where they will stack by gravity, and means in each of said transverse passages for supporting said letters as they stack therein.
20. 2. An automatic mail sorting machine comprising a table supported on legs and having a horizontal wall and a vertical wall, inclined shafts journaled in bearings supported on said walls at opposite ends of said table, means for rotating one of said shafts, a continuous belt extending around said shafts driving the other of said shafts from said one shaft, and a rack supported on said table in an inclined position on top of said belt, said belt underlying the entire bottom of said rack, said rack being partitioned into a plurality of longitudinal passages each terminating at one end at a juncture with a transverse passage, said transverse passages being inclined with said junctures at their tops whereby letters placed in said longitudinal passages will be conveyed therealong by said belt to said transverse passages where they will stack by gravity, and means in each of said transverse passages for supporting said letters as they stack therein.
30. 3. An automatic mail sorting machine comprising a table supported on legs and having a horizontal wall and a vertical wall, inclined shafts journaled in bearings supported on said walls at opposite ends of said table, means for rotating one of said shafts, a continuous belt extending around said shafts driving the other of said shafts from said one shaft, and a rack supported on said table in an inclined position on top of said belt, said belt underlying the entire bottom of said rack, said rack being partitioned into a plurality of longitudinal passages each terminating at one end at a juncture with a transverse passage, said transverse passages being inclined with said junctures at their tops whereby letters placed in said longitudinal passages will be conveyed therealong by said belt to said transverse passages where they will stack by gravity, and means in each of said transverse passages for supporting said letters as they stack therein, the walls of said passages being vertical.
40. 4. An automatic mail sorting machine comprising a table supported on legs and having a horizontal wall and a vertical wall, inclined shafts journaled in bearings supported on said walls at opposite ends of said table, means for rotating one of said shafts, a continuous belt extending around said shafts driving the other of said shafts from said one shaft, and a rack supported on said table in an inclined position on top of said belt, said belt underlying the entire bottom of said rack, said rack being partitioned into a plurality of longitudinal passages each terminating at one end at a juncture with a transverse passage, said transverse passages being inclined with said junctures at their tops whereby letters placed in said longitudinal passages will be conveyed therealong by said belt to said transverse passages where they will stack by gravity, and means in each of said transverse passages for supporting said letters as they stack therein, and bridges spanning the longitudinal walls of said racks and being secured thereto at the tops thereof.
50. 5. An automatic mail sorting machine comprising a table supported on legs and having a horizontal wall and a vertical wall, inclined shafts

journalled in bearings supported on said walls at opposite ends of said table, means for rotating one of said shafts, a continuous belt extending around said shafts driving the other of said shafts from said one shaft, and a rack supported on said table in an inclined position on top of said belt, said belt underlying the entire bottom of said rack, said rack being partitioned into a plurality of longitudinal passages each terminating at one end at a juncture with a transverse passage, said transverse passages being inclined with said junctures at their tops whereby letters placed in said longitudinal passages will be conveyed therealong by said belt to said transverse passages where they will stack by gravity, means in each of said transverse passages for supporting said letters as they stack therein, said longitudinal passages being of narrow width for supporting said letters in substantially vertical position, and said transverse passages being sufficiently wide to receive said letters lengthwise.

5. An automatic mail sorting machine comprising a table supported on legs and having a horizontal wall and a vertical wall, inclined shafts journalled in bearings supported on said walls at opposite ends of said table, means for rotating one of said shafts, a continuous belt extending around said shafts driving the other of said shafts from said one shaft, and a rack supported on said table in an inclined position on top of said belt, said belt underlying the entire bottom of said rack, said rack being partitioned into a plurality of longitudinal passages each terminating at one end at a juncture with a transverse passage, said transverse passages being inclined with said junctures at their tops whereby letters placed in said longitudinal passages will be conveyed therealong by said belt to said transverse passages where they will stack by gravity, and means in each of said transverse passages for supporting said letters as they stack therein, including a box in each of said transverse passages for receiving said letters, a backing plate crossing each of said boxes and being slidably disposed therein, a rod secured to each of said backing plates and extending through a wall of said rack, and a light compression spring mounted on each of said rods between its backing plate and said last mentioned wall whereby said letters move said backing plates due to gravity and their weight and compress said springs as they stack in said boxes.

6. An automatic mail sorting machine comprising a table supported on legs and having a horizontal wall and a vertical wall, inclined shafts journalled in bearings supported on said walls at opposite ends of said table, means for rotating one of said shafts, a continuous belt extending around said shafts driving the other of said shafts from said one shaft, and a rack supported on said table in an inclined position on top of said belt, said belt underlying the entire bottom of said rack, said rack being partitioned into a plurality of longitudinal passages each terminat-

ing at one end at a juncture with a transverse passage, said transverse passages being inclined with said junctures at their tops whereby letters placed in said longitudinal passages will be conveyed therealong by said belt to said transverse passages where they will stack by gravity, means in each of said transverse passages for supporting said letters as they stack therein, including a box in each of said transverse passages for receiving said letters, a backing plate crossing each of said boxes and being slidably disposed therein, a rod secured to each of said backing plates and extending through a wall of said rack, and a light compression spring mounted on each of said rods between its backing plate and said last mentioned wall whereby said letters move said backing plates due to gravity and their weight and compress said springs as they stack in said boxes, each of said boxes having a long side wall opposite from the adjacent longitudinal passage, a shorter side wall opposite said long side wall and a bottom wall extending the length of said long side wall and tapering to a fine edge past said shorter wall, said fine edge lightly engaging said belt, said box being open at its opposite ends.

7. An automatic mail sorting machine comprising a table supported on legs and having a horizontal wall and a vertical wall, inclined shafts journalled in bearings supported on said walls at opposite ends of said table, means for rotating one of said shafts, a continuous belt extending around said shafts driving the other of said shafts from said one shaft, and a rack supported on said table in an inclined position on top of said belt, said belt underlying the entire bottom of said rack, said rack being partitioned into a plurality of longitudinal passages each terminating at one end at a juncture with a transverse passage, said transverse passages being inclined with said junctures at their tops whereby letters placed in said longitudinal passages will be conveyed therealong by said belt to said transverse passages where they will stack by gravity, and means in each of said transverse passages for supporting said letters as they stack therein, the length of the shortest of said longitudinal passages being substantially more than the length of the combined widths of said transverse pas-
